U.S. Appl. No. 29/366,901, filed Jul. 30, 2010, entitled "Dental Syringe," Peuker et al.

(Continued)

Primary Examiner — David Muller(74) *Attorney, Agent, or Firm* — Pamela L. Stewart(57) **CLAIM**

The ornamental design for a dental syringe, as shown and described.

DESCRIPTION

FIG. 1 is a perspective view showing the new design for a dental syringe.

FIG. 2 is a right side view of the design shown in FIG. 1, with the left side being a mirror image thereof;

FIG. 3 is a top view thereof;

FIG. 4 is a bottom view thereof;

FIG. 5 is a front view thereof; and,

FIG. 6 is a back view thereof.

The broken lines form no part of the claimed design, and any shading is provided to illustrate contour only and is not an indication of texture, gloss, etc.
